COMBINED ADVERTISING AND VENDING DEVICE

Mervin A. Elliott, Rockville Centre, N. Y., assignor to
International Latex Corporation, Dover, Del., a cor-
poration of Delaware

Application November 18, 1954, Serial No. 33,160

Term of patent 14 years
(Cl. D80—10)

To all whom it may concern:

Be it known that I, Mervin A. Elliott, a citizen of the United States and a resident of Rockville Centre, Long Island, State of New York, have invented a new, original, and ornamental Design for a Combined Advertising and Vending Device, of which the following is a specification, reference being had to the accompanying drawing, forming part thereof, wherein:

The figure is a perspective view of a combined advertising and vending device, showing my new design.

I claim:

The ornamental design for a combined advertising and vending device, as shown.
